JEROME B. FARMER, OF INDIANAPOLIS, INDIANA.

Letters Patent No. 86,658, dated February 9, 1869.

IMPROVEMENT IN GATE-HINGES.

The Schedule referred to in these Letters Patent and making part of the same.

To all whom it may concern:

Be it known that I, JEROME B. FARMER, of Indianapolis, in the county of Marion, and State of Indiana, have invented a new and useful Improvement in Hinges; and I do hereby declare that the following is a full and exact description of the same, reference being had to the accompanying drawings as a part of this specification, and to the letters of reference marked thereon, like letters always referring to like parts.

The nature of my invention consists in the construction of hinges of variable leverage, (reckoning from the rivet uniting the pair to the place of contact with the door or gate,) wherein the top hinge is similar to ordinary hinges, excepting the rivet-bearing, while the bottom hinge is made to project considerably further from the gate and post to the rivet, and both upper and lower hinge are provided with an hour-glass bearing for the rivets, and by this peculiar construction they have the effect on a gate or door, to raise the same as it swings open, and at the same time keep the top thereof leaning toward the latch-post. In other words, with this hinge on a gate, the gate will always close itself by its centre of gravity remaining on the side next the latch-post.

To enable others skilled in the art to make and use my invention, I will now proceed to describe the same.

Figure 1 is a perspective top view of both hinges.

Figure 2 exhibits the lower hinge in section and partly in detail.

Figure 3 shows miniature hinges on a gate.

A is the "post"-half of the upper hinge, and its construction is very much like the same half of any other hinge in common use.

B is the "gate"-half of the upper hinge, the distinguishing feature of which consists in the peculiar shape of the rivet-bore, or bearing.

C is the "post"-half of the lower or bottom hinge. The base of this piece is similar in shape to the base of the other pieces, but it differs from others in having projecting ears cast on its face, and extending about two inches therefrom. In the outer ends of these ears small holes are drilled to receive the rivet which holds the two halves of the hinge together.

These ears are strengthened and tied together in their base-half by a tapering web, E, fig. 2, cast between them.

The dotted parallel lines J show the position for the rivet in each piece of the lower hinge. (See fig. 2.)

D is the long "gate"-half of lower hinge. Its base is similar to the others, but the elongated neck of the hinge-end is peculiar to this piece only, and distinguishes it from any other hinge. This neck may be

made three inches long, (more or less,) and is cast at an angle of about forty-five degrees from the base.

This lower hinge constitutes the leading feature of my invention.

By making the ears of C two inches long and the neck of D a corresponding length, the rivet J is placed at such a distance from the gate, and so much further than the rivet of the upper hinge, that the gate opens on a tilt or wind, (always leaning shut,) the centre of gravity remaining on the latch-side until the gate is swung entirely open. When it is entirely open, *i. e.*, back against the fence, the centre of gravity changes to the hinge-side so much that the gate will remain open of its own accord.

Fig. 3 represents the position of a gate, partly open, swung by these hinges. It is raised up and over small obstacles in the act of opening.

i., in fig. 2, is the centre bearing of the rivet journal-box, or opening.

By observing the divided rivet-end of D in this figure, it will be seen that the "bearing" for the rivet is almost exactly the shape of an hour-glass, small in the middle and large at the edges.

Both hinges (the upper one as well the lower) have this same "bearing" for the rivet, and this shape gives free swing to the gate when it is thrown out of perpendicular, while the rivet is always held snug and free from play in the middle by the isthmus *i.*

I am aware of the existence of the forked-bottom hinge, made of wrought-iron, having two legs, each leg terminating with a half-circle fork, (or saddle,) and these resting on staples for a base. This hinge performs a similar function to my hinge, but, unlike mine, it will not permit the gate to swing beyond a right angle to the position it occupies when shut, while mine allows it to swing ninety degrees.

My hinge can be made of wrought-iron, though I prefer cast-iron or brass. When on a gate, it gives entire security against breechy animals and careless children, as the gate cannot be opened by the former, nor left open by the latter.

I do not claim as original with me the idea of so hanging a gate or door as to incline it to swing shut by its own gravity; but

What I claim, is—

The combination of elongated necks in the lower hinge of a pair, with an "hour-glass" bearing for the rivets of both upper and lower hinge, all as set forth, and for the purposes described.
